UNITED STATES PATENT OFFICE.

JOHN W. BRAGGER, OF WATERTOWN, NEW YORK, ASSIGNOR TO THE
JEFFERSON BRASS WORKS, OF SAME PLACE.

MACHINE FOR BENDING TUBES.

SPECIFICATION forming part of Letters Patent No. 632,636, dated September 5, 1899.

Application filed December 15, 1898. Serial No. 699,298. (No model.)

To all whom it may concern:

Be it known that I, JOHN W. BRAGGER, a citizen of the United States, residing at Watertown, in the county of Jefferson and State 5 of New York, have invented certain new and useful Improvements in Machines for Bending Tubes; and I do declare the following to be a full, clear, and exact description of the invention, such as will enable others skilled 10 in the art to which it appertains to make and use the same, reference being had to the accompanying drawings, and to the letters of reference marked thereon, which form a part of this specification.

15 This invention relates to improvements in machines for bending tubes; and it consists in mechanism whereby one end of a tube to be bent is held stationary and adjacent to a magazine containing spherical balls, which are 20 adapted to be forced through the tube and made to follow in contact with the end of a mandrel which has been previously passed through the tube, said balls being fed forward through the tubing simultaneously with the 25 swinging of the mandrel in the act of bending the pipe and forcing the mandrel out of the tubing after the latter has been bent to the desired angle.

A further part of the invention relates to 30 means whereby the bent portion of the tube is prevented from bursting while the mandrel is being driven out of the pipe by means of the forward movement of the spherical balls, which are forced through the bend in the tube 35 and against the end of the mandrel. This mechanism comprises a form which is automatically brought into contact with the curved surface of the pipe already bent simultaneously with the forward movement of a 40 plunger which drives the spherical balls through and the mandrel out of the pipe.

A further part of the invention relates to the provision of mechanism, in a tube-bending machine, for automatically locking the reinforcing-form against the bent portion of the 45 pipe while the mandrel is being forced out and releasing the same as the mandrel returns to its starting position.

Another part of the invention consists in 50 the provision of a magazine which is adapted to contain the spherical balls, which are forced

forward by means of a plunger, said magazine having a slightly-longitudinal movement and carrying at its forward end a collar adapted to fit the flanged end of the pipe to be bent, 55 said pipe being gripped and firmly held by means of an operating-lever and toggle-joint mechanism previous to the forward movement of the magazine.

To these ends and to such others as the invention may pertain the same consists, further, in the novel construction and arrangement of parts, as will be hereinafter more fully described and then specifically defined in the appended claims. 65

My invention is clearly illustrated in the accompanying drawings, which, with the letters of reference marked thereon, form a part of this application, and in which drawings similar letters of reference indicate like parts 70 throughout the several views, in which—

Figure 1 is a top plan view of my tube-bending machine, showing the position of various parts previous to the bending of the tube. Fig. 2 is a top plan view of the machine, showing the relative arrangement of the parts after the tube has been bent to the desired angle. Fig. 3 is a side elevation of the machine, showing the geared wheels whereby power is applied to the machine. Fig. 4 is a horizontal 80 section through the magazine and the tube held thereby and adjacent portions holding the magazine and the clamping-gear in contact with the tubing, said view showing the mandrel held within the tube and adjacent 85 to the end of the collar carried by the magazine. Fig. 5 is a vertical section through the machine, taken on line 5 5 of Fig. 1. Fig. 6 is an elevation of one of the cam-wheels mounted on the main operating-shaft. Fig. 7 is a 90 similar view of a second cam-wheel having a groove of a distinct shape and also mounted on the main operating-shaft, and Fig. 8 is a detail view in section showing the manner of attachment of a swinging plate to a geared 95 wheel.

Reference now being had to the details of the drawings by letter, A designates the framework of the machine, which is mounted on suitable legs A', and on brackets A², fastened to said frame, is the operating-shaft B, which shaft is provided with a gear-wheel. 100

B', the teeth of which mesh with the worm B², to which power is transmitted from the pulley B³, which may be driven from any source of supply of power.

- 5 Keyed to the main operating-shaft are the cam-wheels C and C', which wheels have distinctive cam-grooves C² and C³, respectively, preferably of a shape as shown in Figs. 6 and 7 of the drawings. Mounted to travel in the 10 groove C² in said cam-wheel C is an antifriction-roller C⁴, which is mounted on a stub-shaft C⁵, carried in the end of the slide C⁶, which slide is adapted to reciprocate in the dovetailed groove D in the bed of the frame. 15 C' is a lug integral with said slide C⁶ and carries an adjusting-screw C⁸, which is adapted to bear against the end of the plate D', which is provided with an elongated slot and held to the slide by means of a bolt D⁹, passed 20 through said plate D' and slide C⁶. The forward end of said plate D' has a projection D⁴, through which passes a bolt d, engaging with the slide C⁶ and preventing any lateral movement or turning of said plate D'. Mounted 25 horizontally in the aperture in said projection D⁴ is a plunger D⁵, which extends forward and in alignment with the bore of the magazine E, which magazine is provided to contain the spherical balls E². This magazine E, which 30 is cylindrical in shape and open at its ends, has a slight longitudinal movement within the bore of the plate F, which is secured to the frame of the machine by means of bolts F', and the forward end of said magazine is 35 externally threaded to receive the flanged nut F², which is provided to hold the flanged collar F³ to the end of said magazine, this detail being clearly shown in Fig. 4 of the drawings. 40 Pivoted on a bolt g on the top of the frame 45 is the angle-plate G, which is provided with a diagonally-disposed slot G' at the end of its laterally-projecting arm G², and its other end is forked and straddles the end of the magazine and has its arms apertured, as at G³, and 50 designed to engage with the integral lugs G⁴ on diametrically opposite sides of said magazine, whereby as the said plate G rocks on its pivot g the magazine is given a slight longitudinal movement for a purpose which will 55 be presently described.
- Mounted on the bed of the frame and sliding in suitable guideways or dovetailed grooves is the plate H, which plate carries at its inner end the jaw H', which is bolted to said 60 plate, as at h. This jaw has one of its forward corners rounded, as shown clearly in Figs. 1 and 2 of the drawings, which show a top plan view of the same, and has its longitudinal edge, which merges into the curved 65 corner, and one end concaved, forming a suitable member to grip about a portion of the circumference of the pipe to be bent. Opposite the concaved end of said jaw is mounted a longitudinally-adjustable block K, which 70 is held to the frame by means of bolts K'. This block has elongated apertures in which 75 are disposed said bolts, which are rigidly

held to the frame, said apertures being provided for the purpose of allowing a slight longitudinal movement to said block, and an adjusting-screw K², mounted in an upwardly-projecting lug K³, is provided, which may be screwed up against the end of said block in order to hold it securely in a fixed position. Between the concaved ends of said jaw H' 75 and block K the end of the tube to be bent is designed to be securely held during the bending process. The plate H is moved backward and forward by means of a toggle-joint comprising the links H⁹ and H⁶, which are 80 pivoted together and secured to the plates H⁷ and H², respectively, a lever H¹⁰ forming a part of link H⁹, as illustrated. This block H² has an upwardly-projecting lug H⁸, which is apertured to receive a bolt H⁴, which forms a 85 pivot to which the forked end H⁵ of the link H⁶ is pivoted. The forked or inner end of said plate H has bolted securely thereto a plate H⁷, which has integral lugs H⁸, which are apertured to receive a bolt forming a 90 pivotal connection between said lug and the link H⁹, and is pivoted to the link H⁶, thus completing the mechanism forming the toggle-joint. Secured to the edge of the frame adjacent to the block H² is an adjusting-bolt 95 H¹¹, the inner end of which is adapted to bear against the end of said block H² in order to hold it in a fixed position. On a lateral projection H¹² on said plate H⁷ is a lug h', which extends through the diagonally-disposed aperture G' in the arm G² of the angle-lever G, whereby as the toggle-lever is worked back and forth the link H⁷ is reciprocated and said angle-lever caused to rock slightly on its pivot g, which movement imparts a longitudinal motion to the magazine. 100 105

Pivoted on a stationary axis and in a horizontal position directly underneath the forward end of the magazine and the clamping-jaws designed to hold the end of the tube to be bent is a geared wheel L, and securely bolted or otherwise fastened to said wheel L is a block or plate M, and adjustably mounted so as to have a slight longitudinal movement is a block M', the forward or inner end of 110 which is concaved to conform to the circumference of the tube against which said block or plate M' is designed to bear during the bending process. Immediately behind said plate M' and integral with plate M is a lug 115 M², which carries an adjusting-screw M³, which is adapted to bear against the rear end of the adjusting-block to hold the same in a fixed or adjusted position. This block M, which is bolted to the geared wheel L, is designed to turn with the wheel and assume a position at right angles to its starting position. Bolted or otherwise securely fastened to the said block M is the plate N, which has integral lugs N', which are apertured to receive 120 the mandrel O, and a series of cog-teeth N² may be either integral with said mandrel or a rack-bar securely fastened to said mandrel, and N³ is a shoulder on the mandrel, which 125 130

limits its inner throw by coming in contact with one of the lugs N' , forming a part of the plate N . Mounted on a vertically-disposed stud P on the block M is a geared wheel P' , the teeth of which are designed to mesh with the teeth on the mandrel O , and loosely journaled on said stud is an operating-lever Q , which has a lug Q' , which is adapted to strike against a similar lug Q^2 , which is carried by the gear-wheel P' for the purpose of rotating said gear-wheel in the act of imparting a longitudinal movement to the mandrel.

Mounted in the cam-groove O^3 in the wheel C' , which is keyed to the main operating-shaft, is an antifriction-roller R' , which roller is carried by the sliding plate R^4 . This plate R^4 is mounted in a dovetailed portion of the frame, as shown at R^5 in Fig. 5 of the drawings, and bolted or otherwise fastened to said sliding plate is a rack-bar S , having a series of teeth S' on its edge, which are designed to mesh with the teeth of the geared wheel L , as shown clearly in Figs. 1 and 2 of the drawings. In order to rigidly hold and guide said rack, I provide a block Y , which carries an antifriction-roller Y' , mounted thereon, which roller is adapted to contact with the back face of said rack-bar, being located, preferably, opposite the contact-point of the rack and gear. This block may be adjusted by means of the set-screw Z , as shown clearly in Fig. 5 of the drawings.

Mounted in a dovetailed slot and adapted to travel longitudinally in the frame and in a direction at right angles to the magazine is a sliding block T , and mounted adjacent to one of its forward corners is a reinforcing-block T' , having its corner adjacent to the bent portion of the tube concaved or channeled to conform to the circumference or shape of the tube which has been bent. This block T is drawn forward by means of the spring T^2 , which is connected at one end to a stud T^3 , fastened to the swinging block M , while its other end is secured to the plate T , as at T^4 . This reinforcing-block is provided for the purpose of preventing the bursting of the tube which has been previously bent, coming in contact with the curved portion of the tube, while the mandrel is being forced out of the tube in advance of the balls, which are driven forward by means of the plunger, and it will therefore be observed that this reinforcing-block performs no function whatever, either in the bending of the pipe or in the finishing of the same. In order to hold said reinforcing-block in its forward position and adjacent to the curve in the pipe while the mandrel is being driven out, I provide a locking-bar J , which in its locking position is thrown forward and assumes a position behind the lug Q' , which is secured to the plate T , as shown in Fig. 2 of the drawings. This locking-bar J is fastened to the stud J^2 in any suitable manner, it being shown in the drawings as secured by means of a set-screw J^3 , and fastened to the stud J^2 is an arm J^3 , between the free

end of which arm and the frame is disposed a spring J^4 , provided for the purpose of throwing the locking-bar out of the path of the lug Q' , which travels with the plate T . Fastened to said stud J^2 is a screw-threaded apertured arm J^5 , carrying an adjusting-screw J^6 , the inner end of which is disposed in the path of the rack-bar S and struck by the latter as the rack-bar is driven forward at each revolution of the cam-wheel. By adjusting this screw the throw of the locking-bar may be regulated, and the movement of the plate T is so regulated with reference to the forward movement of the rack-bar that said plate will always be drawn down to the position shown in Fig. 2 or at its lowest limit before the rack-bar strikes the adjusting-screw J^6 , which causes the locking-bar J to be thrown over or behind the stud Q' , which securely holds said plate so that its lower corner, carrying the reinforcing-block, will be held rigidly against the bend in the pipe.

The operation of the machine is as follows: The tube to be bent, (shown clearly in Fig. 4 of the drawings and lettered X ,) which is provided with a shouldered portion X' , is inserted between the locking-jaw H' and the block K and in alinement with the bore in the magazine, after which the operating-lever H^{10} is depressed, which causes the toggle-joint to force the said jaw forward to grip the tube about its flanged portion simultaneously with the forward movement of the magazine, which carries the collar at its end adapted to be inserted in the flanged end of the said tube, this forward movement of the magazine being caused by the rocking of the angle-lever G , which is connected at its forked ends to said magazine and actuated by means of the lug h' , which travels in the diagonal slot in the arm of said lever G . The tube thus held between the jaw and the adjustable block K , with the collar held within the flanged end of the tube, the next step is the inserting of the mandrel in the outer end of the tube, this being effected by manipulating the lever Q , which rotates the geared wheel P' , meshing with the rack-bar on the shank of the mandrel. The balls, which have been previously inserted in the magazine, are now ready to be advanced so that the forward one of said balls will contact with the end of the mandrel held within the tubing, said balls being in contact with one another, and in the position described the main operating-shaft is rotated and with it the cam C , which by the peculiar contour of its cam-groove carrying the antifriction-roller, which is connected with the slide D' , will cause said slide to be driven forward slightly in advance of the forward movement of the slide carrying the rack-bar. As said plate D' is driven forward the plunger carried thereby will force the balls forward through the magazine, so that the forward ball will contact with the end of the mandrel, at which moment the slide carrying the rack-bar will be driven forward and in its

forward movement will cause the geared wheel L to rotate, and the block M, which is rigidly held to said geared wheel, will begin to swing and carry with it the mandrel, which 5 has its forward end inserted in the tube to be bent. At the moment said mandrel begins to bend the pipe the plunger D⁵ advances the balls through the tubing, forcing same at the same rate of speed that the mandrel travels 10 and always causing the advance ball to contact with the end of said mandrel during the entire bending operation. After the mandrel has finished its bending operation and assumes a position adjacent to the toggle-lever, in which position it is substantially at 15 right angles to its starting position, the next step is to draw the mandrel out of the tubing. Previous, however, to the driving out of the mandrel the block T has been advanced to the position shown in Fig. 2 of the drawings by means of the spring T², in which position the reinforcing-block T', carried by the block T, is brought so that its concaved corner comes in contact with the bent portion 20 of the tube and is held rigidly in this position by means of the locking-bar J, which after the reinforcing member has been advanced to its farthest limit is turned on its pivot so as to bear against the rear side of 25 the lug Q', this locking member being tilted by means of the rack-bar, which strikes against the adjusting-screw J⁶, which is carried by the lug J⁵, which is keyed to and rotates with the stud J², carrying said locking-bar. The reinforcing member thus being 30 held rigidly about the curved surface of the bent portion of the pipe, the plunger in the further rotation of the cam-wheel C will force the balls forward and drive the mandrel out 35 of the tubing, and the advance balls which follow the mandrel will drop out of the bent tube and fall into a receptacle, (not shown,) which may be held underneath the end of the tube adjacent to the end of the mandrel. 40 The tube thus being bent and the mandrel driven out in the manner described, the cam-wheels finish their revolutions, and at the moment the rack-bar begins its backward movement the locking-lever J will be thrown 45 out of the path of the lug Q', this allowing the plate T to resume the position shown in Fig. 1 of the drawings, said plate T being forced back by the corner of the block M adjacent to the spring connected therewith contact- 50 ing with the inner end of said plate, as will be readily understood. As the rack-bar begins its return movement the gear-wheel L rotates in the reverse direction from that before described and the block M, carrying the 55 mandrel, swings back to the position shown in Fig. 1, so that the mandrel will be in alignment with the bore in the magazine. As the cam-wheel C completes its revolution the plunger, which is connected with the anti-friction-roller, which travels in the groove of 60 the said wheel, will return to its starting po-

sition, and the pipe is now ready to be released from the jaw and adjacent block or stationary jaw clamping the same by raising up the toggle-lever H¹⁰. When the plunger 70 has been withdrawn from the magazine, the balls left in the pipe may be returned to the magazine by gravity, as by setting the machine in a slightly-inclined position, or said balls may be returned in any other suitable 75 way, as by the hand of the operator. The two advance balls utilized in the bending operation, which balls have dropped out into the receptacle, are inserted in the magazine before the operation is repeated for bending 80 the next tube.

While I have shown and described a machine adapted to make ninety-degree bends, it is my purpose to make pipes of various degrees, which may be accomplished by utilizing various cams, which are adapted to shorten or lengthen the throw of the rack-bar which actuates the mandrel-carrying plate and by changing the shape of the concave forming-surface of the jaw which is actuated by the 90 toggle-lever.

Having thus described my invention, what I claim to be new, and desire to secure by Letters Patent, is—

1. A machine for bending pipes, in which independent balls are forced through the pipe to be bent, and made to follow the end of a mandrel during the bending operation. 95

2. A machine for bending pipes, in which balls are forced through the pipe to be bent, and made to follow in contact with the end of a mandrel, while the latter bends the pipe about a former, as set forth. 100

3. A machine for bending pipes in which balls are forced through the pipe to be bent made to follow in contact with the end of a mandrel inserted in the pipe as said mandrel is caused to swing and have a slight longitudinal movement in the pipe during the bending operation. 105

4. A machine for bending pipes, in which balls are contained within a magazine and forced through the pipe to be bent, which is held to receive the balls as they are driven from the magazine, said balls being made to follow in contact with the end of a mandrel as the latter bends the pipe about a former, as set forth. 115

5. In a pipe-bending machine, the stationary and the sliding clamping-jaw, a flanged collar engaging a pipe held by said jaws, a former forming a part of said sliding jaw, a mandrel and swinging member carrying the same, and means for operating the latter while the jaws are held stationary, and in a clamping relation as set forth. 120

6. In a pipe-bending machine, clamping mechanism for holding the pipe to be bent, a magazine and a collar carried thereby, which collar is designed to engage with one end of the pipe, and a mandrel inserted in the other end of said pipe, a grooved former, into whose 130

groove the pipe is bent as the mandrel is caused to swing toward said former, and means for operating the machine, as set forth.

7. In a machine for bending pipes, the clamping members designed to hold one end of the pipe to be bent, a longitudinally-movable magazine carrying a collar adapted to slide in one end of the pipe and the mandrel inserted from the other end of said pipe, and the balls and means for simultaneously forcing the latter through the pipe and operating the mandrel, as set forth.

8. In a machine for bending pipes, clamping mechanism for holding one end of the pipe to be bent, a magazine containing balls, a collar carried at the end of said magazine, means for imparting a longitudinal movement to the latter, a mandrel inserted in the tube, a swinging block carrying said mandrel, a plunger for advancing the balls, and means for actuating said plunger and mandrel-carrying block, as set forth.

9. In a pipe-bending machine, the clamping members designed to hold one end of the pipe to be bent, a former, a toggle-joint, and lever for operating the same, said former mounted to move longitudinally, a magazine and balls carried therein, a pivoted plate connected at one end to the magazine, and rocked on its pivot, as the toggle-lever is operated, combined with the mandrel, and means for operating same, and the plunger and driving mechanism for advancing the balls, as shown and described.

35 10. In a pipe-bending machine, the clamping members designed to hold one end of the pipe to be bent, a grooved former, a toggle-joint and lever for operating the same, combined with a magazine mounted to move longitudinally and balls carried therein, a plunger for advancing said balls in the magazine and through the pipe to be bent, a pivoted plate having connection at one end with said magazine, and provided with a diagonally-disposed slot in which a lug, carried by the toggle-joint mechanism travels, and the mandrel and means for swinging same, as set forth.

50 11. In a pipe-bending machine, the clamping members for holding one end of the pipe to be bent, the toggle-joint and lever, the magazine and pivoted plate for actuating the same, the plunger and longitudinally-movable slide carrying said plunger, the operating-shaft and cam-wheel and connections between the latter and said slide, combined with the mandrel and pivoted mandrel-carrying block, and means for swinging said block, as the balls are being forced through the tube, as shown and described.

55 12. In a pipe-bending machine, the clamping members for holding the pipe, the magazine, the plunger and slide carrying the latter, the operating-shaft, the cam-wheel mounted to turn thereon, an antifriction-roller traveling in a groove in said wheel, and connected to the slide, combined with a

rotary geared wheel and mandrel-carrying block secured thereto, a mandrel and means for rotating the geared wheel, as shown and described.

70 13. In a pipe-bending machine, the clamping members for holding the pipe to be bent, a magazine, the plunger, and slide carrying the latter, the operating-shaft, the cam-wheel mounted thereon, for actuating the slide, combined with a rotary geared wheel and a block secured thereto, a mandrel mounted on said block and a rack-bar engaging with the teeth of the geared wheel and means for imparting a longitudinal movement to said rack-bar, as shown and described.

75 14. In a pipe-bending machine, the clamping members for holding the pipe to be bent, a magazine, the plunger, and slide carrying the latter, the operating-shaft, the cam-wheel mounted thereon for actuating the slide, combined with a rotary geared wheel and block secured thereto, a mandrel mounted on said block and a rack-bar engaging with the teeth of the geared wheel and the slide to which the rack-bar is attached, and cam-wheel for actuating same, as shown and described.

80 15. In a pipe-bending machine, the combination with the clamping members for holding the pipe to be bent, the magazine, and balls, the plunger and means for operating same, the mandrel inserted in the pipe, and mandrel-carrying block, and a reinforcing sliding plate and means for advancing same so as to contact with the pipe after the latter is bent and while the balls are forcing the mandrel out of the pipe, as set forth.

85 16. In a pipe-bending machine, the combination with the pipe-clamping members, the magazine, the balls, the plunger and means for operating the same, the geared wheel, the mandrel and block carrying the mandrel secured to said wheel, the rack-bar meshing with the latter, and operating mechanism for reciprocating the rack-bar, a sliding plate and reinforcing-block mounted thereon, connection between said plate and the mandrel-carrying block, whereby as the latter swings forward, the reinforcing-block is drawn forward so that the recessed portion will bear against the pipe after the latter has been bent, and means for holding said reinforcing-block in such position while the mandrel is being driven out of the pipe, as set forth.

means for operating the same, the geared wheel, the mandrel and mandrel-carrying block secured to said wheel, the rack-bar and mechanism for driving same, the sliding plate 5 and reinforcing-block carried thereon, means for advancing the reinforcing-plate, and a tilting locking-bar, designed to be thrown behind a lug on the plate carrying the reinforcing-plate, said locking-bar being tilted by the 10 rack-bar, as shown and described.

19. In combination with the reinforcing-block and sliding plate carrying the same, the reciprocating rack-bar and means for operating same, the geared wheel and mandrel-carrying block secured thereto, the spring connecting the said sliding plate with the mandrel-carrying block, the stud and locking-bar turning therewith, and a set-screw fastened 15 to said stud and disposed in the path of the 20 rack-bar, and designed to swing the locking-bar behind a lug on said plate, as shown and described.

20. In combination with the sliding reinforcing-block-carrying plate, the stud and 25 locking-bar secured thereto, a rack-bar and means for actuating the same, an arm mounted on said stud, a set-screw carried by said arm.

designed to be struck by the end of the rack-bar, and a spring-actuated member connected to the stud for returning the locking-bar to 30 its normal position, as set forth.

21. In combination with the slide C⁶, the adjustable block secured thereto, a projection D⁴ and plunger carried therein, and a set-screw mounted in a lug on said slide and 35 designed to contact with the end of the block, as shown and described.

22. In combination with the mandrel-carrying block, the mandrel carried in a bracket thereon, a rack-bar secured to said mandrel, 40 a shoulder of the mandrel engaging the edge of one of the ears through which the mandrel passes, a geared wheel meshing with said rack and an operating-lever loosely mounted on the stud on which said gear-wheel is pivoted, 45 and lugs on said handle and wheel designed to contact with each other to rotate the wheel in one direction, as set forth.

In testimony whereof I affix my signature in presence of two witnesses.

JOHN W. BRAGGER.

Witnesses:

A. L. HOUGH,
FRANKLIN H. HOUGH.
